UNITED STATES PATENT OFFICE.

JAMES McKECHNIE AND JULIAN P. CLEAR, OF BARROW-IN-FURNESS, ENGLAND,
ASSIGNORS TO VICKERS LIMITED, OF LONDON, ENGLAND.

PISTON.

1,331,573.

Specification of Letters Patent. Patented Feb. 24, 1920.

Application filed September 12, 1916. Serial No. 119,782.

To all whom it may concern:

Be it known that we, JAMES McKECHNIE and JULIAN PRIME CLEAR, both subjects of the King of Great Britain, residing at Naval 5 Construction Works, Barrow-in-Furness, in the county of Lancaster, England, have invented certain new and useful Improvements in or Relating to Pistons, of which the following is a specification.

10 This invention relates to pistons and connecting rods, more especially those intended for use in internal combustion engines of high power, the chief object of the invention being to provide a connection which is 15 of great strength and distributes the thrust over a maximum surface.

According to this invention a cross pin on the end of the connecting rod is formed with a thrust bearing surface of uninterrupted part- or semi-cylindrical form and the piston is constructed with a cross web that carries a bearing having a correspondingly uninterrupted concave part- or semi-cylindrical surface. In one form of piston the web carrying the said bearing closes 20 the end of one cylinder member on to which is secured a second or lower member also having a web, through which the end of the connecting rod passes, the two cylinder 25 members being connected together with the cross pin between them. The web of the lower member is also formed with a semi-circular recess receiving the under side of the projecting ends of the pin.

30 In order that the said invention may be clearly understood and readily carried into effect we will describe the same more fully with reference to the accompanying drawings, in which:—

35 Figures 1 and 2 are vertical sections of a trunk piston and connecting rod with cross pin connection of the improved type, and

40 Figs. 3 and 4 are similar views to Figs. 1 and 2, illustrating a modification of the 45 trunk piston connection.

Referring to the arrangement shown in Figs. 1 and 2, B is the cross pin on the upper end of the connecting rod E'. D, D' are top and bottom bearing brasses carried by 50 the transverse web f of the piston F, the brass D serving for the unbroken semi-cylindrical face b' of the pin B, while the brasses D' serve to engage the projecting ends of the pin, bearing on the short under

surfaces b². Both brasses are provided with 55 anti-friction metal linings d.

The crosspin B is bolted through the flanges b³ and bolts e⁴ on the inner or upper flanged end e⁴ of the connecting rod E' and the bearing brasses or blocks D, D' are secured inside the piston, the walls of which are unpierced. The main brass D, which is in this case at the top, is bolted to the web f of the piston F, by bolts d⁵ (Fig. 1) and also passed through and secured to the lower brass D', supporting the ends of the pin B, at the short under surfaces b². Four bolts d⁵ are employed, two on each side of the pin B.

The main or unbroken face b¹ of the pin 70 B is the upper one and the piston pressure is directly taken by the full length of this upper face. The pin is hollow and is closed at its ends by the two screwed plugs b⁴. As the cross pin B is entirely inside the piston 75 the piston walls are unpierced.

In the construction illustrated in Figs. 3 and 4, the cross pin B is fixed on the head or flanged end e⁴ of the connecting rod E¹ by the screwed studs e⁵ which screw into the 80 base b³ of the pin, the construction allowing of an increased bearing surface b¹ as compared with that of the pin shown in Figs. 1 and 2, the effective surface b¹ extending through a larger angle. The piston 85 is made in two main parts F¹ and F² bolted together through the webs f¹ and f² by the bolts f³ and at the sides by the long stud bolts f⁴, the upper web f¹ having a semi-cylindrical recess f⁵ which receives the main 90 brass D, while the lower brasses D¹ are held in the recessed parts f⁶ of the lower web. The pin B extends through the piston from side to side, so that the maximum bearing surface is obtained, both circumferentially 95 and longitudinally.

What we claim and desire to secure by Letters Patent of the United States is:—

1. A hollow engine piston for use with a connecting rod having a cross pin providing an uninterrupted part cylindrical bearing surface, a transverse web inside the piston and a cross pin bearing carried by the said web, comprising two members, the upper one of which provides a continuous bearing face for the uninterrupted pin surface while the lower one engages the two projecting ends of the pin. 100 105 110 115

2. A hollow engine piston for use with a connecting rod having a cross pin providing an uninterrupted part cylindrical bearing surface, comprising two main cylindrical members, a connecting transverse web in each member, formed with a part cylindrical bearing surface for the cross pin and means for connecting the two members together with the pin between them.
- 10 3. A hollow engine piston for use with a connecting rod having a cross pin providing an uninterrupted part cylindrical bearing surface, comprising two main cylindrical

members, a connecting web for the outer member formed with an unbroken semi-cylindrical recess receiving the projecting surface of the cross pin, a web on the inner piston member recessed to receive the ends of the cross pin and means for connecting the two piston webs together with the cross pin between the two webs. 15 20

In testimony whereof we herewith affix our signatures.

JAMES McKECHNIE.
J. P. CLEAR.
